VACUUM CLEANER CART

Joe F. Handley, P.O. Box 924, Odessa, Tex. 79760

Filed Mar. 5, 1973, Ser. No. 338,125

Term of patent 14 years

Int. Cl. D6—99

U.S. Cl. D7—170

FIG. 1

FIG. 2

FIG. 3

FIG. 4

FIG. 5

FIG. 1 is a perspective side view illustrating a cart design of the present invention;

FIG. 2 is a three-quarter front perspective view of the cart disclosed in FIG. 1;

FIG. 3 is a front view of the cart disclosed in FIGS. 1 and 2;

FIG. 4 is a top view of the cart disclosed in FIGS. 1, 2, and 3; and

FIG. 5 shows the cart in side perspective with a vacuum cleaner illustrated in broken lines, which broken lines form no part of the claimed design invention.

I claim:

The ornamental design for a vacuum cleaner cart, substantially as shown and described.
